UNITED STATES PATENT OFFICE

104,123

DESIGN FOR A COOKING RANGE

John A. Underwood, Chicago, Ill., assignor to Montgomery Ward & Co., Incorporated, Chicago, Ill., a corporation of Illinois

Application September 5, 1936, Serial No. 64,745

Term of patent 7 years

To all whom it may concern:

Be it known that I, John A. Underwood, a citizen of the United States, residing at Chicago, in the county of Cook and State of Illinois, have invented a new, original, and ornamental Design for a Cooking Range, of which the following is a specification, reference being had to the accompanying drawing, forming a part thereof.

In the drawing the figure is a perspective view of a cooking range showing my new design, the side of the range other than that shown being substantially plain.

I claim:

The ornamental design for a cooking range, as shown and described.

JOHN A. UNDERWOOD.
